UNITED STATES PATENT OFFICE.

WILLIAM WEIR, OF CATHCART, GLASGOW, SCOTLAND.

EVAPORATING AND DISTILLING PLANT.

1,079,966.

Specification of Letters Patent.

Patented Dec. 2, 1913.

Application filed June 3, 1912. Serial No. 701,389.

To all whom it may concern:

Be it known that I, WILLIAM WEIR, a subject of the King of Great Britain and Ireland, residing at Cathcart, Glasgow, Scotland, have invented certain new and useful Improvements in Evaporating and Distilling Plants; and I do hereby declare the following to be a full, clear, and exact description of the invention.

- 10 This invention relates to evaporating and distilling plants such as are commonly employed for the obtaining of fresh water from sea water on board ship. Installations of such plants may comprise one or more evaporators. It is common practice for two evaporators to be arranged side by side with a single condenser placed alongside them, the condenser being of the vertical cylindrical type with vertical tubes. The steam 20 evaporated from the sea water in the evaporators passes from the latter through their uptakes to a common vapor pipe which is arranged above the evaporators and is led downward to the distilling condenser. The 25 available engine room floor space is often very limited, especially in warships; and my invention has for its object to reduce the floor space required by an evaporating and distilling plant.
- 30 With this object in view, my invention consists in a novel construction and combination of elements which will be described in the following specification and more particularly set forth in the annexed claims.
- 35 In the accompanying drawings:—Figure 1 is a front elevation, parts being broken away and parts being shown in section, of a plant according to my invention. Fig. 2 is a cross section on the line *a—a* of Fig. 1 and is drawn to a slightly larger scale than Fig. 1.

a, a are the two evaporators arranged vertically side by side, and *b* is the condenser which latter is of the cylindrical tubular type. The shell of the condenser, at or near its two ends, is swelled as shown at *c, c*, and a cylindrical plate *d* is riveted or otherwise attached to the shell at this swelled portion so as to form an annular 45 chamber *e* between the plate and the shell. Each evaporator is arranged to communicate with one of these annular chambers by means of a short coupling piece *f* which 50 communicates on the one hand with the steam space in the evaporator and on the other hand with the annular chamber *e*.

A sluice valve *g* is provided for the purpose of controlling the flow of steam through each of these coupling pieces. Perforations *h* are formed in the upper portions of the plates *d* which perforations serve to admit to the condensing chamber *p* of the condenser the steam which rises from the evaporators through the coupling pieces *f* and the annular chambers *e*. The steam is condensed on the exterior surface of the tubes *k*, cold water being circulated through the tubes in the usual manner.

m indicates the circulating water inlet and *n* the circulating water outlet; but both the inlet and outlet may of course be at the same end of the condenser, the arrangement depending on whether there is an odd or even number of water passes.

At the bottom of the condenser and at or about the center of its length, a connection is provided for a pipe *o* through which the air can be withdrawn by an air pump.

The employment of steam-control valves of the sluice type allows of the coupling pieces *f* being of short length so that the condenser *b* is raised very little above the tops of the evaporators and, as I prefer to employ evaporators of a type in which the height is less than usual, the total height of the plant can be kept quite moderate and need not be much, if any, greater than is now usual for plants of equal evaporative capacity. Moreover, as the steam is admitted to the condensing chamber *p* at the top and at the ends of the latter, and as the air pump suction is at the bottom of the chamber and about midway between the ends, and as the steam is admitted to the chamber through a large number of holes, the flow of steam over the cooling surface is fairly uniform, and the condensation is very well distributed over the cooling surface, thus allowing of the employment of a condenser of minimum cooling surface and therefore minimum size.

The number, shape, and arrangement of the perforations may be varied as may be thought desirable. It is, however, an essential feature of my invention that the perforations are only in the upper portion of the plates *d*.

The steam in passing through the annular chambers *e* and through the perforations in the plates *d* tends to deposit on these plates and on the swelled portion of the condenser shell, any particles of brine which may have

been carried up with it from the evaporators. Any brine so deposited drains back into the evaporators; and the arrangement and construction of apparatus according to 5 my invention is therefore useful in preventing or reducing the admission of salt to the condensing chamber of the condenser.

Having now described my invention, what I claim as new and desire to secure by 10 Letters Patent is:—

1. In evaporating and distilling plant, in combination, a pair of evaporators arranged vertically, side by side, a condenser arranged horizontally above the said evaporators, annular steam chambers arranged to surround the steam condensing chamber of said condenser, one at each end of said chamber, and provided with perforations in their upper portions adapted to admit the 15 steam to said chamber, short passages arranged to connect the two evaporators with the two annular steam chambers, each to each, and sluice valves adapted to control the flow of steam through the said short 20 passages.

2. In evaporating and distilling plant, in combination, a pair of evaporators arranged vertically, side by side, a condenser arranged horizontally above the said 25 evaporators, annular steam chambers arranged to surround the steam condensing chamber of said condenser, one at each end of said chamber, the said annular chambers being formed between swelled parts of the 30 condenser shell and plates—perforated in their upper portions—located within these swelled parts, short passages arranged to connect the two evaporators with the two annular steam chambers, each to each, and 35 sluice valves adapted to control the flow of steam through the said short passages.

3. In evaporating and distilling plant, in combination, a pair of evaporators arranged vertically, side by side, a condenser arranged horizontally above the said 40 evaporators, annular steam chambers arranged to surround the steam condensing chamber of said condenser and to communicate therewith, one at each end of said chamber, short 45

passages arranged to connect the two evaporators with the two annular steam chambers, each to each, sluice valves adapted to control the flow of steam through the said short passages, and an air pump suction connection at the bottom and center of 50 length of the steam condensing chamber.

4. In evaporating and distilling plant, in combination, a pair of evaporators arranged vertically, side by side, a condenser arranged horizontally above the said evaporators, annular steam chambers arranged to surround the steam condensing chamber of said condenser, one at each end of said chamber, and provided with perforations in their upper portions adapted to admit the steam to said 55 chamber, short passages arranged to connect the two evaporators with the two annular steam chambers, each to each, sluice valves adapted to control the flow of steam through said short passages, and an air pump suction connection at the bottom and center of 60 length of the steam condensing chamber.

5. In evaporating and distilling plant, in combination, a pair of evaporators arranged vertically, side by side, a condenser arranged horizontally above the said evaporators, annular steam chambers arranged to surround the steam condensing chamber of said condenser, one at each end of said chamber, the 65 said annular chambers being formed between swelled parts of the condenser shell and plates—perforated in their upper portions—located within these swelled parts, short passages arranged to connect the two evaporators with the two annular steam chambers, each to each, sluice valves adapted to control the flow of steam through the 70 said short passages, and an air pump suction connection at the bottom and center of 75 length of the steam condensing chamber.

In testimony whereof I have signed my name to this specification in the presence of two subscribing witnesses.

WILLIAM WEIR.
